UNITED STATES PATENT OFFICE.

CHARLES L. WAGANDT, OF BALTIMORE, MARYLAND.

DESIGN FOR A MUFFIN-PAN.

SPECIFICATION forming part of Design No. 35,478, dated December 24, 1901.

Application filed November 29, 1901. Serial No. 84,147. Term of patent 3½ years.

To all whom it may concern:

Be it known that I, CHARLES L. WAGANDT, a citizen of the United States, residing at Baltimore, in the State of Maryland, have invented and produced a new and original Design for Muffin-Pans, of which the following is a specification.

Reference is to be had to the accompanying drawings, in which—

Figure 1 is a top plan view of a muffin-pan embodying the features of the design, and Fig. 2 is a side edge view of the same.

The essential feature of the design consists of the shape and configuration of the muffin-pan illustrated in the drawings, in which appears a flat rectangular plate containing a plurality of circular cups extending below the said plate and on whose bottom appear in relief different-shaped figures. On one of said circular bottoms appears a Maltese cross

with wedge-shaped panels between its arms, on another a series of concentric rings, on another a rosette with straight radial arms, on another a rosette with sinuous radial arms, on another an octagonal star-shaped figure, each arm of the star having curved outlines and concentric rings in the center of the figure, and on another a five-pointed star-shaped figure, the extreme points merging into the circular wall of the cup.

I claim—

The design for a muffin-pan herein shown and described.

In testimony whereof I affix my signature in the presence of two witnesses.

CHARLES L. WAGANDT.
